CLAIM

The ornamental design for a laboratory fume hood, as shown and described.

DESCRIPTION

FIG. 1 is a front elevational view of a laboratory fume hood showing our new design;

FIG. 2 is a right side elevational view thereof, the left side being a mirror image of the right side shown; and FIG. 3 is a top plan view thereof, the bottom and rear being plain and unornamented.

The back and bottom of the laboratory fume hood are not visible during normal usage.
